WALL EASEL

Dieter Fichtel, Muskegon, Mich., assignor to American
Store Equipment Corporation, Muskegon, Mich.

Filed Apr. 29, 1971, Ser. No. 138,864

Term of patent 14 years

Int. Cl. D19—07

U.S. Cl. D25—1 R

FIG. 1.

FIG. 2.

FIG. 3

FIG. 4.

FIG. 5.

FIG. 6.

FIG. 7

FIG. 8

FIG. 9.

FIG. 10.

FIG. 1 is an elevational view of one face of the easel;
 FIG. 2 is an elevational view of the opposite face of the easel;

FIG. 3 is a plan view of the easel;

FIG. 4 is a side elevational view of the easel;

FIG. 5 is an elevational view of one face of an alternative embodiment of the easel, having the same design as that disclosed in FIG. 1, but being one-half the width of the FIG. 1 easel;

FIG. 6 is an elevational view of the opposite face of the easel shown in FIG. 5 with the chalk tray seen in FIG. 2 removed;

FIG. 7 is an elevational view of the same face of the easel as is shown in FIG. 1, with wood veneer being applied thereto;

FIG. 8 is an elevational view of the same face of the alternative embodiment easel as is shown in FIG. 5 with a wood veneer being applied thereto;

FIG. 9 is a cross-sectional view taken along plane IX—IX of FIG. 1 and showing the configuration of the easel frame;

FIG. 10 is a cross-sectional view taken along plane X—X of FIG. 1 and showing the configuration of the frame at the bottom of the easel with a chalk tray adhered thereto;

I claim:

The ornamental design for a wall easel, as shown and described.
